25 Claims. (Cl. 175—369)

The invention of this application relates to electrical panelboards and parts thereof.

The principal object of the primary invention of this application is to sectionalize panelboards of the so-called "feeder type", that is to say, one wherein the circuits leading from the panelboard are of a large variety of electrical capacities and characteristics, in such a manner that no extravagance of space is permitted.

10 Sectionalizing of panelboards has been satisfactorily accomplished in connection with lighting distribution panelboards, these possessing the enabling characteristic that the circuits leading therefrom are generally of similar capacity and 15 nature. Because of this similarity, the problem of sectionalizing a lighting distribution panelboard is a relatively simple one.

However, for feeder panelboards, wherein the 20 circuits are of widely dissimilar capacities and characteristics and where an infinite number of combinations must be effected, sectionalizing is not so simple a matter.

While sectionalizing a panelboard of this type is not in itself a difficult matter, harmonizing 25 the demands of sectionalizing with the demands of space economy, and the demand of not having too many sizes and types of units, is a very difficult problem and until my solution was offered, there had been no satisfactory sectionalized 30 panelboards of the feeder type.

It is observed at the present time that if the demands of space economy are to be ignored, sectionalizing of feeder type panelboards could be effected merely by cutting up a panelboard into a 35 large number of units. This would provide large units and small units of various sizes and it would be obvious that a unit large enough to receive large circuit elements would be quite wasteful of space if used to receive small circuit ele- 40 ments.

Further, because of the fact that a feeder panelboard must accommodate an infinite variety of circuit capacities, circuit characteristics, and combinations, sectionalizing such a panelboard at 45 first appeared impractical because of the fact that it was thought that an infinite variety of units would have to be made and carried in stock to meet various conditions. Merely to indicate the variety of circuit capacities, characteristics, etc., 50 there is presented here a table showing the various demands made upon feeder panelboards:

1. Poles—circuits may be of 1, 2, 3, 4, or 5 poles;
2. Amperage capacities—circuits may be of 30, 55 60, 100, 200, 400, 600, 800, 1200 Amp. etc.;

3. Voltages—circuits may be of 125, 250, 440, 575, or 660 volts;

4. Bus bar connections—circuits may be connected in any of the following ways:

4—4 wire; 3—3 wire; 2—2 wire; 3 ϕ to single ϕ ; 60 2 ϕ to single ϕ ; 2 ϕ 3-wire to 2 ϕ 4-wire and to 2 ϕ 5-wire; 3-wire 110-220 volt single ϕ ; the same with branches of 110 volt 2-wire -220 volt 2-wire; 110-220 volt 3-wire, etc.

These merely exemplify the numerous demands 65 that must be satisfied, by feeder panelboards.

A solution of the problem of sectionalizing feeder panelboards, consistent with the demands of space economy, and the demands of manufacturing economies, insofar as the variety of units 70 to be carried is required, etc., is the principal object of the primary invention of this application. A key to my solution may be found in my discovery that the advantages desired may be gained by proportioning the divisions of the panelboard 75 so that the dimensions of a panel built up of these divisions will be integral multiples of the greatest common factors of the corresponding dimensions of the divisions without, at the same time, necessarily being integral multiples of the 80 corresponding dimensions of the divisions themselves. In other words if the length dimension is considered by way of example, a dimension characteristic that is intimately associated with the result that an economy of space is effected will 85 be found to be this; the length of a panel will be an integral multiple of the greatest common factor of the lengths of the divisions, and yet may not be an integral multiple of the lengths of divisions. That is to say, I establish a defin. 90 relation between the length of the panel and the greatest common factor of the lengths of the divisions, but no such relation necessarily exists between the length of the panel and the lengths of the divisions; the relation established is to the 95 factor and not to the division lengths.

In illustrating my invention, I have chosen, from a large variety of units, units of the "A", "B", "C", "C₁", and "D" type, combined to form SA, SB, SB₁, SB₂, SC, SC₁, and SD circuit protect- 100 ing divisions, and these have been chosen only by way of illustration of the many possibilities which my invention possesses.

Further, I have chosen to illustrate, as my units, units of the plug and receptacle type, or of the movable head and fixed base type, and this type is chosen only by way of illustration.

Further objects of the invention are to provide 105 novel details of construction of circuit protecting 110

units, combined in circuit-protecting-divisions to form a sectionalized panelboard.

Other objects of the invention will presently appear upon reference to the following detailed description of a panelboard built in accordance with my invention and of units useful in forming the panelboard of my invention, the panelboard and these units being shown in the appended drawings in which

60 Figs. 30 and 31 are diagrammatic views of a panelboard layout, circuit-protecting-units only being diagrammatically indicated in Fig. 30 and complete-circuit-protecting-divisions only being diagrammatically indicated in Figs. 31 and 32.

The panel (Figs. 30—31)

65 The panelboard of the invention includes a panel made up of a plurality of complete-circuit-protecting divisions mounted on a fixed plate (not shown) and over bus bars 125, the circuit 70 protecting elements of the divisions being electrically connected to the bus bars by screw bolts cooperating with the threaded holes H therein, spaced at uniform distances "X".

75 As a matter of definition the following terms will be defined: A panelboard includes a "panel"

and the associated mounting plate, box, etc. A panel includes a number of circuit protecting divisions grouped in an ordered appearance fashion; the term "panel" may embrace all of the units in any one distributing center, or it may embrace less than all of the units in any one distribution center.

80 A "circuit-protecting-division" includes a desired grouping of "circuit-protecting-elements," (fuses, switches, etc.,) capable of adequately protecting a complete circuit, and associated with mounting and assembling body parts of insulating material, both the elements and their associated body parts being included in the word "division".

85 A "unit" is an article of manufacture including insulation blocks and circuit protecting elements, and may comprise a portion of a block of insulating material, as in the case of the "D" units, or one or more blocks of insulating material, (as in the case of two "A" units combined) or portions of one or more blocks of insulating material, (as in the case of "B" units combined)

90 and the combination of a block and those elements that happen to be thereon, is hereafter referred to as a "unit", whether the same forms a complete-circuit-protecting division, or only part of a division, or a part of two or more divisions.

95 Further, in case the units are of the plug and receptacle fused switch type, as shown, a plug and its receptacle together, are to be considered as a "block".

100 "Capacity" is the maximum load carrying ability, in amperes, of the part under consideration. The "capacity" of a unit is its maximum load-carrying ability, in amperes. The "capacity" of a panel is equal to the sum, in amperes, of the capacities of the units comprising the panel.

105 From Fig. 31, it will be seen that the divisions shown are of assorted widths, across the bus bars, and assorted lengths along the bus bars, this being due principally to the different dimensions of the elements thereof. For example, where the elements are in the nature of low voltage fuses, the divisions are generally narrow, and where the elements are in the nature of high voltage fuses, the divisions are wide. Also, divisions of the 2 pole type are comparatively shorter than similar divisions of the 3 pole type.

110 It might be well to mention at this time that the dimensional size of a fuse varies with its capacity. For example, a 60 Amp. fuse is larger in cross section than a 30 Amp. fuse and smaller than a 100 Amp. fuse, etc. Because of this, a division which can accommodate fuses up to 200 Amp. 115 size, cannot accommodate a 400 Amp. fuse, etc., but a division which can accommodate a 400 Amp. fuse can also receive a smaller capacity fuse, provided it be equipped with fuse receiving means of the proper size, spacing, and type. The assortment of divisions shown diagrammatically in Figs. 31 and 32 will be briefly described.

120 The division referenced "SA" in my design is 11" wide and 4X(5") long. The division referenced "SD", is 11" wide and 4X(5") long. The 125 divisions referenced "SC" are each 5½" wide and 3X(3¾") long. The divisions referenced "SC₁" are each 5½" wide, and 3X(3¾") long. The divisions referenced "SB" are each 5½" wide and 6X(7½") long. The division referenced "SB₁" is 11" wide and 2X(2½") long. The 130 divisions referenced "SB₂" are each 5½" wide and 4X(5") long.

135 A characteristic of each division is its compactness, each being substantially as compact as pos- 140

sible, consistent with the requirements that the elements thereof be properly insulated, supported, grouped, etc., and consistent with manufacturing tolerances.

5 For convenience of manufacturing, the divisions can be built up of units, and a representative selection of units for the divisions of Figs. 31-32 is shown in Fig. 30 by way of example.

The "SA" division may be made up of two "A" units, 11" x 2X each. The "SD" division may be made up of one "D" unit, 11" x 4X. The "SC" divisions together may be made up of one "C" unit, 11" x 3X, double branch type. The "SC₁" divisions together may be made up of one "C₁" unit, 11" x 3X, double branch type. The "SB" divisions may together be made up of three "B" units, 11" x 2X, double branch type.

Further, where "SB₁" and "SB₂" divisions are substituted for the "SB" divisions of Fig. 31, as in Fig. 32, these may be made up as follows: The "SB₁" out of one "B" unit, 11" x 2X, double branch type; the "SB₂" out of two "B" units, 11" x 2X, each of the double branch type.

Other examples may be mentioned but are here omitted for purposes of brevity.

Each of the panels shown, therefore, includes the following units, all 11" wide; 2—"A" units, 3—"B" units, 1—"C" unit, 1—"C₁" unit; 1—"D" unit; or eight units in all, forming eight divisions, Fig. 31, or nine divisions, Fig. 32.

The units, together form a panel, which is enclosed in a cabinet whose gutter plates cover the side edges of the panel formed of the units, and because of this, to preserve an ordered appearance it is not necessary that the units be all exactly 11" wide. Some may be 10½" wide and some 11½", for example, without disturbing the ordered appearance of the board.

Further, mounting means (not shown in Figs. 40 30-31) are provided and these also may be spaced at uniform distances X.

It will be observed at this time that the mounting and connection spacing X is only a fraction of the length of the shortest unit, being one-half 45 of the "A" and "B" length, and is accordingly a fraction of the length of the shortest division.

Further, certain of the unit lengths are fractional multiples of other unit lengths, C:B, C:A, for example, due to the fact that the units and 50 divisions are designed to be as compact as possible, notwithstanding the fact that some of the unit lengths are non-fractional multiples of other unit lengths. I can effect interchange of divisions and of units, without leaving gaps between 55 divisions and units, this being due to the fact that the mounting and connection spacing "X" is less than the unit length, and that each unit length is a non-fractional multiple of "X".

Further, by virtue of the fact that the dimensional characteristics or areas of circuit protective elements are substantially proportional to their electrical characteristics or capacities, it will be seen that the areas of divisions, compacted to such elements, will prove to be similarly 65 proportional to their capacities. Thus, a panel having a certain arrangement of divisions, and consequently a certain area, will have a certain capacity and will always accommodate enough units to total substantially that capacity. This 70 insures against overloading of the feeders of a panel already installed, by rearrangement of units, and also permits utilization of the feeders, and the panel area to practically 100% capacity, regardless of what rearrangements of divisions take place. This feature, together with

other features of design, permits replacement of one arrangement or group of divisions by different ones, without there being any danger of disturbing the ordered appearance of the panel, without creating odd-size gaps in the panel, without overloading the panel feeders, and without sacrifice of compactness of the panel as a whole.

Further, the divisions are subdivided into units, and these are combinable in various ways to form different types of divisions. For example, a 7X division may be made of two 2X units plus one 3X unit, or of a 4X unit plus a 3X unit or of a 2X unit plus a 5X unit, etc. Or, a batch of 2X, 3X, etc., units may be grouped at one time to form 7X divisions, at another time 5X divisions, etc. Thus, where two circuits whose divisions have a total length of let us say, 12X are to be replaced by five circuits totalling the same capacity and also totalling 12X in length, the replacement can readily be effected without gaps, as will be illustrated by considering the five circuit divisions, 12X in length, being made up of three 2X units and divisions and two 3X units and divisions.

The method of laying out a sectionalized panel-board system 100

In order to design a manufacturing system for sectionalized panelboards, wherein all of the demands of sectionalizing are adequately and satisfactorily carried out, while retaining a satisfactory compactness for the panelboard, I adopted a novel method of laying out my system and I now describe it, since it aids in a complete understanding of my invention, although I do not now claim this method in this application.

I. First, I determined what complete-circuit-protecting divisions would have to be provided by my system. In doing this, I created the desired groupings of the circuit-protecting-elements, listing all of these desired groupings. For example, I discovered that among the groupings would be the following: 3-30 Amp. 250 V. fuses; 2-30 Amp. 250 V. fuses; 3-100 Amp. 600 V. fuses, etc.

II. I then proceeded to arrange the individual elements of each group on body parts of insulating material, to form divisions, in such a way that each division would be as compact as possible, consistent with the electrical and mechanical demands of insulation, strength, spacing, etc. 120 and manufacturing tolerances. I discovered that in general, the divisions could be divided into two widths; about 5½", and about 11", respectively. I therefore, determined to observe the following rule as regards the widths of any divisions I might design. I maintained for the widths of the divisions, dimensions equal to integral multiples of a common factor width, and discovered that a practical common factor width 125 would be 5½", and that the two widths I would provide would be 5½" and 11".

III. I also discovered that because of the compact arrangements there resulted a large variety of lengths of divisions, the lengths varying from about 2½" up to about 7½", with intermediate 140 lengths, at about 3¾", 5", 6¼", etc.

IV. I then determined for that assortment of lengths a proximate common factor, which proved to be in my design, 1¼", I, therefore, redesigned my divisions so that their lengths 145 would be integral multiples of the common factor length. The lengths were found to be as follows: 2½, 3¾", 5, 6¼, 7½, etc.

V. For convenience of manufacture, and also in order to reduce the number of lengths from 150

the five mentioned to three, I subdivided the divisions into units. In certain cases, areas, were so subdivided that a number of units would form a complete division (SA). In another case, a number of units formed a number of divisions (SE). In still another case, one unit formed two divisions (SC—SC₁). In another case, one unit formed one division (SD).

VI. I then proceeded to provide means for connecting the elements of the division to the bus bars and means for mounting the units on the fixed structure, usually the mounting plate. I provided threaded holes in the bus bars to receive connection screws and also provided on the mounting plate threaded holes to receive mounting screws. I spaced the threaded holes of the bus bars and of the mounting plate on uniform spacings equal to the common factor length $1\frac{1}{4}$ ". I did this in appreciation of the fact that my lengths of divisions (and of units) varied, not as integral multiples of the length of the shortest division (or unit), but as integral multiples of the common factor length, and I appreciated that if the uniform spacing was chosen, not with relation to the length of the shortest division, but with relation to the common factor length, I could accommodate, with complete interchangeability, the intermediate lengths of divisions, that is those lengths which were not integral multiples of the length of the shortest division. A characteristic of my lay out, therefore, is the following relation, shown in Fig. 30.

The spacing of the bus bar connection holes and of the mounting holes is equal to a common factor "X", and this common factor, though it is the largest common factor of all the division (and unit) lengths, is less than the length of the shortest division (and unit).

Because of this relation, each of my divisions (and units) is as compact as possible, and yet I am able to interchange the divisions without having gaps between them and without sacrificing compactness, except for manufacturing tolerances.

A still further relation is this: The overall length of the panel is an integral multiple of the greatest common factor of the unit lengths, and yet it is not necessarily an integral multiple of any unit length. For example, a complete panel could be built up of 2A units, 1D unit, 1C unit, and 3B units, in which case the panel length would be $17X$. This would be an integral multiple of X (the factor) but would not be an integral multiple of $2X$ (the length of the shortest unit). The same applies to a panel including all but the C unit of the panel of Fig. 30.

As an example of the space efficiency of my design, wherein the above mentioned relation is a characteristic, I contrast the lay out disclosed in Figures 30 and 31 with a similar capacity lay out, wherein the uniform spacing is equal to $(2X)$ the length of the shortest division or unit, rather than, as on my design, where the uniform spacing "X" is one-half of the length of the shortest unit. From Figs. 30 and 31, it will be seen that the length of the panelboard shown is $20X$ or $25"$. Now, if the spacing had been $(2X)$ equal to the length of the shortest unit, I would not have been able to provide C or C₁ units of the $3X$ length, but would have had to provide for these, lengths of $4X$. Accordingly, my "SC" and "SC₁" sections would be "4X" long rather than "3X" long. Altogether, the panel would be $22X$ or $27\frac{1}{2}"$ long. By my design, therefore, I save $2X$ or $2\frac{1}{4}"$ on the panel shown which is a saving of

about 10%, all due to the fact that my divisions are compact and the uniform spacing "X" is a fraction of the length of the shortest section and unit.

Greater savings in length result where the number of $3X$ and $5X$ sections is comparatively great.

Now having described a representative panel-board, and my layout method, I describe in detail two only of the units I provide, these being chosen by way of example.

In Figs. 1-5 I show an "A" unit; in Figs. 9-13, I also show an "A" unit, having a testing plug, and in Figs. 19-29, I show a "B" unit.

The "A" unit

The "A" unit shown in Figs. 1-5 is a plug and receptacle type switch having a fuse therein to protect the circuit line leading from the bus bar to which the receptacle is connected.

The receptacle part 20 is provided with four legs 21 dividing its under portion into three channels or compartments for the accommodation of the three bus bars 125. At each end of said receptacle there is an opening (23 and 24) extending from the corresponding channel into the receptacle. Each of these openings (23 and 24) has a connecting opening 25 leading out of the end of the receptacle.

The floor of the receptacle covers the central channel and part of the side channels and shields the interior of the receptacle from the bus bar space, and is provided with a low cross-rib or barrier 26 immediately over one of the intermediate legs 21.

Secured to the floor of the receptacle 20 as by screws 27 and extending from barrier 26 to the end wall beyond opening 24 and preferably bent so as to lie below opening 25 is a conducting plate or bar 28 carrying at its outer end a pair of fixed or receptacle contact fingers 29 which extend well up above the receptacle floor but whose upper ends are considerably below the top of the walls thereof and below the inwardly projecting shielding portions 30.

At the other end of the receptacle floor is a second bar or plate 28a, similar to plate 28, except that it is not so long, as it overlies only one channel.

Also within receptacle 20 and secured to barrier 26 as by screw 31 passing through hole 31c thereof is a strip of insulating material 32, shown in plan in Fig. 5. This strip 32 may be designated the "fuse limiting" strip and is provided with a plurality of pairs of screw holes, carefully located, through which preventive forks or limiting members or stops 33 may be selectively attached thereto. These stops are shown in Fig. 1 as secured in holes numbered 3 and 5, Fig. 5.

The plug part 50 of the unit is of insulating material shaped to fit within the upper portion of the receptacle and is provided with a suitable hand grip 51 on its outer face, which may consist of a metal plate too short to extend from one pair of fingers 29 to the other so that when the block 50 is inserted top down there can be no current flow and all live parts are hidden. The edges of the plug are cut away from the edges of the plate, as shown, to provide finger grip cavities 51a, Fig. 3.

The under side of plug 50 carries at each end plug contact and fuse prongs, which, for the 30 Amp. 250 V. fuse shown in Fig. 1, comprise plug contacts 52, attached to plates 53 secured

any "A" unit receptacle 20, so as to be completely interchangeable with non-testing "A" unit plugs. At one of its ends, the testing plug may be similar to any non-testing "A" unit plug 50. At its other end however, the testing plug 50T is provided with a large cavity 75 opening to the under face of the plug and having a small opening 76 to the upper face. The conducting plate 53aT to which the fuse 58 is attached at the end containing the cavity 75 does not extend to the end of the plug 50T but projects beyond the edge of the cavity only for a short distance. The plug contact 52T, adapted to coact with a contact 29 in the receptacle 20, is formed on a small plate 53bT secured to the plug as by screws 54cT, which plate 53bT, has a vertical extension 77 extending up into cavity 75 at one end thereof, near opening 76.

Plate 53aT and the parts connected directly therewith are shown more in detail in Figs. 11, 12, and 13. To one end of plate 53aT is fixed an L-shaped spring abutment 78 and back of this, one end of a flexible lead 79. To the other end of lead 79 is fixed a small plate 80 provided with curved ends 81 as shown. Fixed to the end of lead 79 adjacent plate 80, is one end of a coil spring 82, whose other end is fixed to the upright portion of the L-shaped abutment 78. Lead 79 and the spring 82 are of such construction as to allow the plate 80 to be pressed firmly against part 77 of plate 53bT.

The electric connection in this form of plug, from the contact 29 in one end of member 20 to the contact 29 in the other end thereof is through contact 52T to part 77, to plate 80, through lead 79 to plate 53aT, then through the fuse 58, to plate 53 and the other contact 29.

By means of this form of block and the form of bipolar instrument terminal shown in Figs. 9, 40, 12, and 13, an instrument may be connected to the circuit line in series or disconnected therefrom without opening the circuit line or interrupting current flow therethrough.

The form of terminal shown consists of two plates 100 of conducting material connected to the two poles of the instrument, and secured on opposite sides of a thin strip of insulating material 101 which may project a short distance beyond the ends of the plates.

When the tip of this device is inserted in opening 76 it easily separates the upper end of plate 80 from part 77, while the spring 82 holds the lower end of plate 80 in contact with part 77 until plates 100 have contacted with parts 77 and 80 respectively, thus maintaining the one circuit until the other is also completed. The reverse operation occurs upon withdrawal of the terminal, the circuit through the instrument being maintained until the parts 77 and 80 are once more in contact and the main circuit is completed.

An "A" unit plug is adapted to be used with any "A" unit receptacle to form a switch. Placing the plug in the receptacle with the fuse outward breaks the circuit and indicates that the circuit is broken, and placing it in the receptacle, with the fuse inside, completes the circuit, and indicates that fact.

It should be noted that the plug of Figs. 1-5 is identical in shape and outer dimensions with the plug shown in Figs. 9 to 11 and interchangeable therewith so that one may be substituted for the other without change and tests carried out when desired without interruption of service.

It will be observed that while parts 20 and 50

are named as receptacle and plug, they might well be termed base and head, etc.

The "B" unit

This unit, shown in Figs. 19-29, includes two integrally formed receptacles, and two separate plugs therefor, each receptacle and its plug forming half of a "B" unit. The unit is of the same dimensions as the "A" unit and is interchangeable therewith, as can be readily seen.

The "B" unit includes a cup shaped part 120 formed of suitable insulating material, and including end legs 121 and intermediate legs 122, the latter containing suitable bores 123 through which may be passed bolts for securing the part 120 to a suitable supporting base, not shown.

The bottom of the cup shaped part is provided with three suitably spaced "knockouts" 124 providing means through which connection may be made between the elements inside the part and the bus bars 125, which latter are mounted in any suitable fashion on the supporting base, between legs 121 and 122, as indicated. In the drawings, one of the "knockouts" is removed, and a screw 56 and bushing 56a are shown as replacing that knockout.

Inside of the part 120 and at its ends, suitable terminal connecting plates 126 are mounted and to these may be bolted lead terminals, 127. These plates 126 extend across the floor of the cup shaped part too close to one wall of the same, and have secured thereto vertically extending receptacle contacts 128 lying close to the said wall and under an overhanging insulating portion 130 formed thereon. The exposed halves of the contacts 128 are provided with protecting cover pieces 131 of insulating material. The provision of parts 130-130 protect the normally live contacts 128 against accidental touching when the receptacles are open.

In the central portion, the part 120 is provided with a metallic plate 135 overlying the central knockout and one of the others whereby this plate may be connected to anyone of the three bus bars over which the receptacle is to be placed. This plate 135 is provided with two sets of receptacle contacts 128a located on opposite sides of the cross center line of the part 120 and on opposite sides of the longitudinal center line thereof, so that, when the part 120 is divided into two receptacle compartments by means to be described, each will have receptacle contacts in diagonally opposite corners.

With the plates 126 and 135 in position, the part 120 is divided into two receptacles or compartments by a removable insulating wall or shield 140 slidably in guides 141 provided for this purpose. The wall 140 preferably carries also a cover piece 142 of insulating material which overlies the plates 126 and 135 so that when this wall 140 unit, which is shown in Fig. 26, is in position, all of the live parts are guarded against accidental touching.

One of the two plugs 150 is shown in detail in Figs. 20, 21, 27, and 28 as consisting of a portion 140 of insulating material of such size as to fit and fill one of the receptacles and a suitable bail 151, therefor, is provided to aid in withdrawing the plug.

The side of the plug opposite the bail 151, is 145 provided with depending side walls 152 which aid in piloting the plug into proper position for engagement of the plug contacts 153 carried thereby with the receptacle contacts 128, 128a. These plug contacts 153 are mounted at diagonally op- 150

to the plug as by screws 54 passing through the block and having their heads sunk well below the upper surface, out of contact with hand plate 51. Plates 53 extend from near the central portion of the plug to close to the ends thereof and have the contacts 52 at their outer ends where they are in position to mate with contacts 29 of the receptacle. To their inner ends are attached fuse clips 55 for the reception of the 30 Amp. 250 V. fuses 58 for which the device is adapted. It will be observed that each structure 52-53-55 is considered as a plug contact and fuse prong.

With a bus bar 125 electrically connected to plate 28 by a screw 56 and a bushing 56a, extending through the center hole 56b in the floor of the receptacle 20 and into the bus bar hole H, as shown clearly in Fig. 1, replacing the "knockout" that had been in hole 56b, and with a load cable 57 secured to plate 28a by screw 57a as shown in the same figure, the connection through the fuse 58 from bar 125, to cable 57 is made by inserting the plug 50 into the receptacle, with contacts 52 engaging contacts 29.

Fig. 1 shews the plate 28 connected through center hole 56b to the center bus bar 125, and cable 57 connected to plate 28a. If the plate 28 is to be connected to the bus bar in the right hand channel, for a differently phased connection, screw 56 and bushing 56a are placed through the right hand connection hole 56c, the "knockout" 56d at that point being removed, just as the center "knockout" had been for the connection shown. If the plate is to be connected to the bus bar in the left hand channel, the unit as a whole is reversed 180°, and the screw 56, passed through the hole 56c, will align with the left hand bus.

It will be observed that the two holes 56b and 56c through which screw 56 and bushing 56a may pass and which open the interior of the receptacle to the bus bar channels are normally closed, one being closed by the unremoved "knockout", and the other by the bushing and screw, and this is normally true regardless of which bus bar is connected to strap 28. The "knockouts", therefore close the bus bar compartments in back of the units. To complete the closure of the receptacle floor, an insulation sheet 56e is secured to the receptacle floor at opening 23.

Fuse limiting

The plugs of various "A" units are constructed so as to be interchangeable, and for this reason I provide means for preventing the plugging-in of an "A" unit plug having a fuse of higher amperage or lower voltage into an "A" unit receptacle which should not receive such a fused plug and such means will now be described.

In general such means includes preventive forks 33 so mounted in the receptacle as to prevent insertion of a plug having an improper fuse. The forks are adjustable and removable and are used according to the schedule shown in Fig. 5.

The unit shown in Figs. 1-4 happens to be arranged for the reception of a 30 Amp. 250 V. fuse, which is the smallest dimensioned size fuse for which the unit is adapted. As so arranged, the fuse ends are received in clips 55 and the forks are positioned in holes 3 and 5 (Fig. 5), this spacing permitting the insertion of an "A" unit plug having a 30 Amp. 250 V. fuse.

If a plug is equipped with a 60 Amp. 250 V. fuse, the fuse ends will be received in clips 55a (Figs. 14-15), which are so positioned on their

prongs that they will be to one side of the longitudinal center line of the unit, and so that they would engage the forks 33 if the latter were set in holes 3 and 5 for a 30 Amp. 250 V. fuse. A receptacle whose forks are spaced for a 30 Amp. 250 V. fuse could not therefore receive a 60 Amp. 250 V. fuse or any larger dimensioned size fuse. To permit the receptacle to receive a 60 Amp. 250 V. fuse, the receptacle forks would have to be placed in holes 2 and 6, as indicated.

If a plug is equipped with a 100 Amp. 250 V. fuse (Fig. 18), the fuse ends, formed as blades, would be positioned in the parallel blade clips 52e (Fig. 7) formed on a plate 52b having a plug contact 52d and a tongue 52c, the prong structure 52b, 52c, 52d, 52e, replacing the structure 52, 54, 55, of Figs. 1-4. If a plug so equipped were inserted into a receptacle intended to receive plugs having fuses of lower amperage, the forks 33 of that receptacle would engage parts of the structure 52b-52e, preventing complete insertion. To permit the receptacle to receive a 100 Amp. 250 V. fuse, the forks would have to be set in holes 1-7 of plate 52, Fig. 5.

If a plug is equipped with a 200 Amp. 250 V. fuse, referenced 60, (Figs. 6 and 16), the fuse ends 61, formed as blades, would be positioned in the parallel blade clips 62 formed on plate 52a, the latter having a plug contact 63, a tongue 62c, and a fuse holding screw 62a, structure 52a, etc., replacing the structure 52-55 of Figs. 1-4. If a plug so equipped were inserted into a receptacle intended to receive plugs having fuses of lower amperage, the forks 33 of that receptacle would engage parts of the structure 52a, etc., preventing complete insertion. To permit the receptacle to receive a 200 Amp. 250 V. fuse, the forks would be omitted entirely.

If a receptacle is equipped to receive a 30 Amp. 600 V. fuse (Fig. 17) the insertion of a plug having a 60 Amp. 250 V. fuse cannot be effected since the clip 55a of that plug would be engaged by the fork 33 of the receptacle.

From these examples it may be seen that the parts may be so arranged as to prevent the insertion of a plug 50 carrying a standard fuse of either higher amperage value or lower voltage value than that for which the parts are set.

Ganging

Fig. 8 shows the possibility of grouping three "A" units over a common three bar arrangement to form a 3 pole "SA" division, similar to the 2 pole "SA" division of Fig. 31. It shows for example, the three "A" units connected to the three bus bars 125 selectively, with one of the units reversed 180° in position. The plugs of the three units are "ganged" to form a 3 pole switch, by a plate 250, connecting the three plugs, and connected to each of them by screws 251. This plate is so connected to the plugs by the screws that the plugs can move slightly on the plate, relatively to one another, to compensate for difficulties in plugging in, and thus facilitating insertion or plugging in of the 3 pole switch.

It will be understood that the "ganging" principle may be applied to any division, and for example, two or more "B" unit plugs may be "ganged", if desired.

Testing plug

In Figs. 9 to 13 is shown an "A" unit having a plug, in which means are provided for the insertion into the circuit line of a testing or measuring instrument. The testing plug may be used with

80

145

posite corners of the plugs, each being one branch of an L-shaped plate 154 secured to the plug at one end. These plates 154 are provided with suitable tapped openings by means of which fuse holding clips or fingers 155 are bolted thereto. The tapped openings referred to are several in number and so located that several sizes of fuses may be provided for. The form shown in Figs. 20 and 27 for example, is for a fuse having a round end, while that in Fig. 28 is for a cartridge fuse having a blade end.

As it is intended that a plug carrying a fuse 156 may be placed in its compartment in reversed position when it is desired to maintain the circuit broken, means are provided to hold the plug 150 securely in such position. This means may consist of a small plate 160 bent over one edge of the plug and having the bent over edge cut nearly across so as to provide a tongue 161 having a teat 162 adapted to coact with the side wall of the receptacle 120 when the plug is reversed, and inserted.

Further, in order to provide means for testing the fuses without removing plugs 150, openings 165 (Fig. 23) are provided through the plugs 150 from their outer to their inner faces, within the area covered by plates 154. These openings permit the insertion of contact wires or rods connected with any suitable indicator (not shown).

30 A means to prevent exchange of the plugs of two or more "B" units is indicated in Fig. 23, in which figure the plugs are shown as provided with slots 175 cooperating with screws 176 projecting through side walls of the receptacles. It is of course obvious that other plugs, not so slotted, could not be inserted, in such receptacles, when the screws are in position. Other forms of projections and slots may of course be used to accomplish a like purpose.

40 This case is in part a continuation of application, Serial No. 175,173, filed March 14, 1927, on Electric fusing devices.

Summary

45 From the foregoing, it will be seen that there has been provided a sectionalized panelboard whose units may be provided with means to prevent the combining with any unit of a fuse larger than the one intended to be used with that particular unit, the means being adjustable and removable so that the fuse receiving characteristics of the units may be varied as desired.

It will further be seen that there has been provided a sectionalized panelboard having units on 55 to which circuit protective elements, such as fuses, may be assembled and connected into or disconnected from the circuits, without danger to the operator; that is, insertion or removal of fuses into their clips can be accomplished only 60 when the circuits through the fuses are dead. Further, the units are so constructed that fuse replacement can be effected only when the operator is remote from the live parts of the panelboard, or is completely shielded therefrom by insulation.

Further, the panelboard is so constructed that units may be readily converted to and from testing type from and to non-testing type, and when of the testing type, circuit testing may be carried on without interrupting or disconnecting the tested circuit.

Further, it will be observed that each unit while adaptable for several sizes of circuit protective elements (fuses) is only slightly larger in 75 dimension than the largest element (fuse) for

which it is designed, this feature causing the units to be as compact as efficiently possible.

Further, it will be observed that suitable barrier constructions between opposite polarity parts are provided, the barriers facilitating the compacting of the units, by reducing the sizes thereof.

Further, it will be observed that the panel-board is so constructed that all the desirable operations such as changing of circuits, refusing, rephasing, installing units, testing, etc., which require manipulating of the manipulable screws, etc., in the receptacle, may be accomplished from the front side of the panelboard.

It will further be observed that a wide range of convertibility is assured, even though a small assortment of units is provided, the units being combinable so as to create a great variety of divisions, as to size, capacity, number of poles, etc.

It will further be observed that since the panel-board is of the sectionalized type, it possesses all of the advantages inherent to sectionalized panelboards, and that this is accomplished without sacrifice of compactness or convertibility, even though the circuit requirements are of a wide range, as necessary for power distribution contra-distinguished from lighting distribution.

Further, each unit is so constructed that the interior thereof is completely shielded from the live or bus bar space in back of the unit, either by the "knockouts" which had not been removed or by the screw and bushing inserted, in a hole wherein a knockout had been removed.

Further, a great degree of interchangeability is provided by the fact that "A" units are interchangeable with "B" units, etc., and parts of "A" units are interchangeable with parts of other "A" units, etc. Further, by virtue of the fact that the units can be connected selectively to any bus bar, convertibility is assured.

Further, the provision of the insulating plates adjacent the floor of the receptacles, combined with the overhanging portions of the receptacle walls and other insulating pieces, completely shields the live parts of the receptacles.

Further, the various types of units have interchangeable, and standardized mounting and connection details, which enhances the interchangeability and convertibility of the panelboard.

Further, by virtue of the specific type of connection and mounting means provided, interchange of units is facilitated, and may be accomplished from the front of the panelboard, this also applying to rephasing of the units, that is to say, disconnecting them from the bus bars to which they had been connected and connecting them to different bus bars. Further, working on units, without disturbing other units, or the circuits therethrough, is readily possible.

Now having described preferred embodiments of my invention, reference will be had to the following claims for a determination of the scope of my invention.

I claim:

1. In a panelboard of the class described, a plurality of spaced bus bars and a plurality of closely adjacent circuit protective units mounted in front of and over and connected to said bus bars, each unit having a plurality of depressions on the back thereof spaced in a manner corresponding to the spacing of said bus bars so that when a unit is placed over said bus bars, each depression will align with a bus bar to form a compartment for each bus bar, and a "knockout" 145

145

150

in each depression integral with said unit, whereby any desired one of the "knockouts" may be removed to expose any desired one or more of the bus bars to the front of the unit, the "knockouts" when in place serving as an insulating shield between a bus bar and the front side of the units, the "knockouts" being accessible from the front of the panelboard for removal.

2. In a panelboard of the class described, a plurality of bus bars, a plurality of contacts fixedly mounted with respect to each of and spaced along said bars, a plurality of heads having contacts adapted to engage the fixed contacts and means to mechanically connect two or more of said heads to operate in unison whereby a "ganged" head may be formed, said means being readily releasable from and attachable to said heads so that the latter may be operated independently or in unison interchangeably, said means when attached permitting a slight movement of a head relative to its neighbor to compensate for difficulties in interengaging contacts, due to friction, or misalignment.

3. In a panelboard of the class described, a plurality of bus bars each having a plurality of threaded apertures therein, a cup shaped, contact-containing connection receptacle disposed in front of and over said bus bars, a plurality of conducting parts disposed within said receptacle, and a plurality of manipulable parts disposed within said receptacle and selectively adapted to cooperate with one another, and with the threaded apertures, for mounting and connecting purposes, all of said parts being wholly manipulable from the front of the panelboard.

4. In a panelboard of the class described, a plurality of bus bars, units comprising a plurality of similarly constructed bases fixedly connected to said bus bars, and a plurality of similarly constructed removable heads, said heads being adapted to selectively and interchangeably cooperate with said bases, and means attachable to and detachable from said units whereby undesirable interchange of heads and bases is prevented.

5. In a panelboard of the class described, three parallel, equally spaced bus bars, and a plurality of bases over and in front of said bus bars, each of said bases being provided with two holes therethrough for the reception of members adapted to contact with two of the bus bars, the holes aligning with an end and a center bus bar, and a "knockout" in each hole, the bases being symmetrical about the center bus bar.

6. In a panelboard of the class described, three parallel equally spaced bus bars and a plurality of units over and in front thereof, each having end and center contacts adapted to engage the end and center bus bars, the ends of each unit being identical in shape so that the unit may be reversed 180° to permit the end contact to engage the other end bus bar, without disturbing the ordered appearance of the unit in the panelboard.

7. In a panelboard of the class described, a plurality of bus bars, units having contacts exposed to the sides thereof nearest the bus bars, and sheets of insulating material removably secured to said units to form barriers between the bus bars and the contacts or to expose said contacts to the bus bars.

8. In a panelboard of the class described, a plurality of bus bars, a plurality of head receiving bases in front thereof, all having substantially the same width and lengths equal to integral multiples of a predetermined common factor length, and all having identical connection de-

tails whereby they may be interchangeably connected to said bus bars, certain of said bases being constructed to receive one wide head and certain being constructed to receive a plurality of narrower heads, said bases and said heads comprising mutually cooperating bodies upon which are disposed mutually cooperating contacts, the latter being inaccessible when the heads are in mutually cooperative relation.

9. In a panelboard of the class described, a plurality of bus bars, a plurality of head receiving bases in front thereof, all having substantially the same width and lengths equal to integral multiples of a predetermined common factor length, and all having identical connection details whereby they may be interchangeably connected to said bus bars, certain of said bases being constructed to receive one wide head and certain being constructed to receive a plurality of narrower heads, said bases and said heads comprising mutually cooperating bodies upon which are disposed mutually cooperating contacts, similarly sized and shaped heads being relatively interchangeable, said bases being provided with means to prevent the combining therewith of any but the head or heads which that base is intended to receive.

10. In a panelboard of the class described, a plurality of closely adjacent units having removable heads, a plate connected to and extending across a plurality of said heads to form a multi-head switching unit, the heads being movable relatively and with respect to the plate to permit quick-switching action.

11. In a panelboard of the class described, a plurality of closely adjacent plug and receptacle units, means for mechanically connecting two or more plugs to operate in unison as a "ganged" plug, said means being readily releasable from or attachable to said plugs so that they may operate independently or in unison, said means when attached permitting a slight movement of a plug relative to its neighbor to compensate for difficulties in plugging in, due to friction.

12. In a panelboard, of the class described, a plurality of bus bars, a plurality of cup shaped, plug receiving receptacles thereon, all having substantially the same width and lengths equal to non-fractional multiples of a predetermined common factor length, and all having identical mounting details, whereby they may be interchangeably mounted on said bars, certain of said receptacles being constructed to receive one wide plug, and certain being constructed to receive a plurality of narrower plugs, said plugs and said receptacles each comprising a body of insulating material upon which are disposed mutually cooperating contacts, the latter being inaccessible when the plugs and receptacles are in cooperative relation.

13. In a panelboard, of the class described, a plurality of bus bars, a plurality of cup shaped, plug receiving receptacles thereon, all having substantially the same width and lengths equal to non-fractional multiples of a predetermined common factor length, and all having identical mounting details, whereby they may be interchangeably mounted on said bars, certain of said receptacles being constructed to receive one wide plug, and certain being constructed to receive a plurality of narrower plugs, said plugs and said receptacles each comprising a body of insulating material upon which are disposed mutually cooperating contacts, the latter being inaccessible when the plugs and receptacles are in coopera-

- tive relation, the plugs carrying fuses which are enclosed within the receptacles when the plugs are plugged in.
14. A sectionalized panelboard of the dead front convertible type including a plurality of fixed bus bars, a plurality of units having bases fixedly mounted with respect to said bars and connected to one or more of them by selective connectors, each unit being provided with circuit protective elements and with a head carrying means to connect said elements, said heads being movably mounted with respect to said bases so as to be movable to and from circuit connection position, the units being provided with cartridge fuse receiving means, adjustably mounted therein so that each unit may accommodate differently sized fuses, the mounting of the heads being such that each head is maintained in assembly, with respect to its base, whether it is in circuit making or in circuit breaking position, the position of the head revealing at a glance whether the circuit therethrough be made or broken, the heads of similar units being similar in construction so that interchange of heads, as well as adjustment of fuse receiving means in the units, is permissible without disturbing the ordered appearance of the panelboard, each unit being provided with removable means to prevent the receiving thereby of any but a fuse for which it is intended.
15. A sectionalized panelboard employing a plurality of adjacent units which are relatively interchangeable without disturbing the ordered appearance of the panelboard as a whole, each unit being provided with adjustably mounted and replaceable means for receiving and holding a cartridge fuse, so that different sizes and types of fuses on a unit may be interchanged, each unit including a fixed base and a movable head carrying the fuse receiving means, the heads of various units being interchangeable for fuse interchange, each base being provided with removable means for preventing the mounting thereon of any but the head for which it is intended.
16. A sectionalized panelboard including a plurality of bus bars, a plurality of units, each of which is provided with circuit protective elements including convertible and replaceable cartridge fuse receiving means, and each of which is further provided with relatively movable switch-functioning members, means accessible from the front of the panelboard for connecting the units to one or more of the bus bars as desired, before or after the panelboard is formed as a whole, the means being so interlocked with respect to the switch-functioning members that exposing the means for connecting them to bus bars is not possible unless and until the switch functioning members have been moved to the position in which they break the circuit through the unit.
17. A sectionalized panelboard including a plurality of bus bars, a plurality of units, each of which is provided with circuit protective elements including convertible and replaceable cartridge fuse receiving means, and each of which is further provided with relatively movable switch-functioning members, means accessible from the front of the panelboard for connecting the units to one or more of the bus bars, as desired for phasing and rephasing, before or after the panelboard is formed as a whole, the means being concealed by the switch functioning members, when they are in a circuit making position, so that exposing the means for a re-phasing is not possible unless and until the switch-functioning members have been moved to the position in which they break the circuit through the unit, the cartridge fuse receiving means being similarly interlocked with respect to the switch-functioning members.
18. A sectionalized panelboard including a plurality of bus bars, a plurality of units, each of which is provided with circuit protective elements including convertible and replaceable cartridge fuse receiving means, and each of which is further provided with relatively movable switch-functioning members, means accessible from the front of the panelboard for connecting the units to one or more of the bus bars, as desired, before or after the panelboard is formed as a whole, the means being so interlocked with respect to the switch-functioning members that exposing the means for connection to bus bars is not possible unless and until the switch-functioning members have been moved to the position in which they break the circuit through the unit, the cartridge fuse receiving means being similarly interlocked with respect to the switch functioning members, the units being interchangeably mounted on the panelboard, the construction as a whole being such that interchange of units, adjustment, interchange or replacement of fuses, and changes of phasing are all impossible of performance while there is a current through the unit considered.
19. A sectionalized panelboard including a plurality of bus bars having uniformly spaced connection means, a plurality of circuit protective units mounted over and connected to said bus bars, means for connecting the units to any one or more of the bus bars, the units having lengths equal to integral multiples of the spaces between said connection means, each of said units having therein adjustable and interchangeable cartridge fuse receiving means and having switch functioning members, the latter being so mounted that access to the live parts of the units is not possible until and unless the switch functioning members have been moved to their circuit interrupting positions.
20. A sectionalized panelboard including a plurality of bus bars having uniformly spaced connection means, a plurality of circuit protective units, mounted over and connected to said bus bars, means for connecting the units to any one or more of the bus bars, the units having lengths equal to integral multiples of the spaces between said connection means, whereby the units may be interchangeably mounted on said bus bars, each of said units having therein adjustable and interchangeable cartridge fuse receiving means and having switch functioning members, the latter being so mounted that access to the live parts of the units is not possible until and unless the switch functioning members have been moved to their circuit interrupting positions, all of the units being of the same width, so as to present an ordered appearance when combined to form a panelboard.
21. A sectionalized panelboard including a plurality of bus bars having uniformly spaced connection means, a plurality of circuit protective units, mounted over and connected to said bus bars, means for connecting the units to any one or more of the bus bars, the units having lengths equal to integral multiples of the spaces between said connection means, whereby the units may be interchangeably mounted on said bus bars, each of said units having therein adjustable and interchangeable cartridge fuse receiving means and having switch functioning members, the latter being so mounted that access to the live parts of the units is not possible unless and until the switch functioning members have been moved to the position in which they break the circuit through the unit.

switch functioning members have been moved to their circuit interrupting positions, the switch functioning members indicating at a glance, by their position, the condition of the circuit through them and the unit being considered, the connecting means for the units including parts to which access for connection purposes, can be had from the front of the panelboard, the parts being interlocked with the switch members, so that access thereto for connection can be had only when the circuit is interrupted.

22. A sectionalized panelboard including a plurality of bus bars having uniformly spaced connection means, a plurality of circuit protective units, mounted over and connected to said bus bars, means for connecting the units to any one or more of the bus bars, the units having lengths equal to integral multiples of the spaces between said connection means, whereby the units may be interchangeably mounted on said bus bars, said units having therein adjustable and interchangeable cartridge fuse receiving means and having switch functioning members, the latter being so mounted that access to the live parts of the units is not possible until and unless the switch functioning members have been moved to their circuit interrupting positions, the switch functioning members indicating at a glance, by their position, the condition of the circuit through them and the unit being considered, the switch functioning members including relatively movable switch parts having fuse receiving means and one of which covers the other part to enclose the fuse within the interior of the unit.

23. A relatively large area sectional panelboard including a plurality of fixedly mounted bus bars having uniformly spaced connection means, a large number of relatively small area, closely adjacent circuit protective units mounted over and connected to said bus bars by connecting means within the units and accessible from the front thereof, said units having lengths equal to integral multiples of the spaces between said connection means, whereby the units may be interchangeably mounted on said bus bars, each of said units having therein switching means so constructed that access to the bus bar connecting means is prevented unless and until the current through said unit has been interrupted, each of the units also having therein means for receiv-

ing cartridge fuses, said fuse receiving means being adjustably mounted in the unit so that different sizes and types of cartridge fuses may be mounted in a unit without the latter's being disturbed except insofar as adjustment of the fuse receiving and holding means is concerned.

24. A sectionalized panelboard including fixed bus bars having uniformly spaced connection means thereon, a plurality of circuit protective, fused, current leadoff units connected to said bus bars by said connection means, said units having lengths equal to integral multiples of the spaces between said connection means, phasing means selectively and interchangeably connecting said units to one or more of said bus bars, said units being also provided with adjustable fusing means for holding and connecting any one of a number of different sizes and types of cartridge fuses, control means for the units, the construction as a whole being such that the phase and fuse characteristics of each circuit may be varied by interchange of the units and/or of the control means thereof, therein, the said phasing and fusing means being interlocked with respect to the control means in each of the units so that any changes in the phase and fuse characteristics of a unit cannot be made until the current through the unit has been interrupted.

25. A relatively large area sectional panelboard comprising a board having a plurality of fixedly mounted bus bars having uniformly spaced connection formations, a large number of relatively small area, closely adjacent, interchangeable circuit protective fused, current lead-off units connected to said bus bars by connecting means cooperating with said connection formations, said units having different lengths, equal to integral multiples of the spaces between said connection formations, the units being provided with relatively movable, switch-functioning members, interchange of the units being possible without disturbing the ordered appearance of the panelboard as a whole, access to the means for connecting the units to the bus bars being impossible unless and until the switch functioning members have been moved to the position in which they break the circuit through the unit being considered.
